US0D1058866S

(12) **United States Design Patent** (10) Patent No.: **US D1,058,866 S**
(45) Date of Patent: ** Jan. 21, 2025

(54) **PROJECTOR**

(71) Applicant: **Shenzhen Baishi Connected Technology Co., Ltd.**, Shenzhen (CN)

(72) Inventors: **Lu Peng**, Shenzhen (CN); **Yinxiang Mei**, Shenzhen (CN)

(73) Assignee: **Shenzhen Baishi Connected Technology Co., Ltd.**, Shenzhen (CN)

(**) Term: **15 Years**

(21) Appl. No.: **29/955,322**

(22) Filed: **Jul. 31, 2024**

(51) LOC (15) Cl. **16-02**

(52) U.S. Cl.

USPC **D16/229**

(58) **Field of Classification Search**

USPC D16/221, 225, 229, 230, 231, 234, 235;
D21/514

CPC G03B 21/16; G03B 21/14; G03B 21/145;
G03B 21/142; G03B 21/00; G03B 21/001; G03B 21/003; G03B 21/12

See application file for complete search history.

(57) **CLAIM**

The ornamental design for a projector, as shown and described.

DESCRIPTION

FIG. 1 is a front perspective view of a projector, showing our new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is an enlarged detail view of area 9 in FIG. 2.

The broken lines in the drawings illustrate the portions of the projector, which form no part of the claimed design.

The dash-dot-dash broken lines encircling the enlarged views are for annotative purposes only and form no part of the claim thereof.
